UNITED STATES PATENT OFFICE

2,429,444

GRAPPLE

James Yett, Artemus, Ky.

Application January 28, 1946, Serial No. 643,845

2 Claims. (Cl. 294—99)

1

This invention relates to an improved grapple to be used in removing articles from wells, pipelines or any place that is inaccessible due to the size of the cavity or depth thereof.

An object of the invention is to provide a device that is simple, comprising a very few parts and easily operated, to grasp the desired article.

Another object of the invention is to provide a device that is durable and can be inexpensively manufactured and retailed at a reasonable cost.

With the above and other objects and advantages in view, the invention consists of the novel details of construction, arrangement and combination of parts more fully hereinafter described, claimed and illustrated in the accompanying drawing, in which:

Figure 1 is a side view of an embodiment of the invention in position for grasping an article;

Figure 2 is a sectional view of the device;

Figure 3 is a side view of the device in collapsed condition;

Figure 4 is a side view of the device in grappling position;

Figure 5 is a sectional view of the latching means for the device;

Figure 6 is a sectional view on the line 6—6 of Figure 5;

Figure 7 is a fragmentary sectional view of the latching means and the operator for unlatching said means;

Figure 8 is a sectional view on the line 8—8 of Figure 5;

Figure 9 is a fragmentary view of the operator for the latching means;

Figure 10 is a perspective view, partly in section, of the lower end of the grapple;

Figure 11 is a perspective view, partly broken away, of one form of the toothed portion of the grapple, and

Figure 12 is a fragmentary view, partly in section, of another form of an article engaging portion.

Referring more in detail to the drawing, the reference numeral 10 designates the grapple which comprises substantially U-shaped body 12, having inwardly curved apertured ends 14 to which are removably secured by means of fasteners 16 the apertured end 17 of the toothed article graspers or catchers 18. The body 12 is made of spring metal which urges the ends 14 thereof into the position shown in Figure 3. The base end 20 of the body 12 is apertured at 22 to slidably receive the control rod 24, having an eye 26 formed on one end thereof for connection with a cable 28 and adjacent this end, the rod 24 is

2

provided with a transverse stop pin 30 which abutting the outer face of the base end 20 of the body 12, limits the downward movement of the rod 24. Spaced from the pin 30 and positioned inwardly of the body 12 is a second stop pin 32 which abutting the inner face of the base end 20, limits the upward movement of the rod 24 as well as acting as means for supporting the body 10 on the rod 24.

10 Secured to the body 12 adjacent the base end 20 in inverse relation thereto by means of fasteners 34 is the U-shaped apertured rod guide 36 which receives and guides the movement of the rod 24.

15 Positioned inwardly of the body 12 intermediate the guide 36 and the apertured ends 14 is the latch 38 which comprises the hinge 40, one leaf 42 of which is welded to one of the inner sides while the other leaf 44 is welded to the leaf 46 of a second hinge 48. The leaf 50 of the hinge 48 is free and abuts the stop pin 52 in the body 12 when the latch is in operative position.

The hinges 40 and 48 so co-act as to form a substantially unitary latch which is pivoted by 25 means of the hinge 40, but when engaged by the lower tapered end 54 of the rod 24 will quickly collapse, as shown in Figure 4, to grasp the article 56.

30 In operation, the latch is positioned as shown in Figure 1, the grapple is then lowered into the cavity by means of the cable 28 and when the bottom is reached, lowering of the rod 24 will collapse the latch 38 to operate the body 12, as shown in Figure 4.

35 In Figure 12, another form of catchers 58 is shown removably fastened to the ends 14 and it is to be understood that other forms may also be used as desired.

40 It is believed that the operation of the device will be apparent to those skilled in the art and that it is to be understood that various changes in the details of construction, arrangement and combination of parts may be resorted to without departing from the spirit of the invention and the scope of the appended claims.

45 Having thus described the invention, what is claimed as new and desired to be secured by Letters Patent is:

50 1. In a grappling device, a U-shaped body formed of spring metal normally urging the legs of the body together, said legs having inwardly curved portions, toothed catchers attached to the curved portions, a first hinge member having one leaf attached to a first leg of the body, a second hinge member having a leaf attached to the other

leaf of the first hinge, the other leaf of the second hinge being arranged to engage the second leg of the body to hold the legs apart, and a rod passing through the body to engage the hinge members to disengage the other leaf of the second hinge from engagement with the second leg to allow the catchers to be urged towards each other.

2. The structure set forth in claim 1 further characterized by a guide attached to the legs for the rod, a pin on the rod to limit the downward movement of the rod towards the hinges, and a pin on the rod to limit the movement of the rod from the hinges.

JAMES YETT.
